UNITED STATES PATENT OFFICE.

ANTOINE FRANCE, OF LIEGE, BELGIUM.

PLANT FOR WASHING MINERALS BY MEANS OF LIQUID STREAMS.

Application filed November 27, 1926, Serial No. 151,123, and in Belgium December 30, 1925.

The present invention relates to an improvement in mineral washing plant of the kind comprising launders wherein the classification according to specific gravity takes place in a so-called "horizontal stream."

In such plant there are usually provided for the discharge of the products of high specific gravity upward stream or other separators, arranged at intervals along the bottom of the launder and which comprise one or more compartments opening out into the bottom of the launder.

When the great width of the launder renders uncertain the conditions required for an efficient operation of the said separators owing to the difficulty of obtaining the required uniformity of the liquid and solid streams which pass through the compartments of the said apparatus, over the whole width of the latter and of the launder, it becomes useful, instead of multiplying the number of the washing launders in order to reduce their width and subsidiarily that of the separators for the discharge of the products of high specific gravity, to divide the washing launder by one or more longitudinal vertical partitions, and the improvement according to the present invention consists in adopting a similar arrangement in the separators themselves, either by extending the partition or partitions of the launder into the compartment or compartments of the said separators, or in arranging the said partitions in such a manner that they will constitute together with the other walls of the compartment or compartments gradually narrowing orifices, which may be adjustable, thus providing what may be termed distinct apparatus which are however connected to a single aperture for the discharge of the products of high specific gravity at the base of the said apparatus.

Besides the regularity of the streams which it is possible to obtain in this manner over the whole surface of the slot in the bottom of the launder where each separator opens out into the latter, the improvement according to the invention conduces to a considerable advantage in this sense that a single aperture for the discharge of the products of high specific gravity treated in a launder of great width makes it possible to obtain an effective section for the exit of the downward streams more reduced than if one had to employ multiple orifices for this same width, as indeed in such case each of the said orifices must have

a section of which the minimum size is dependent chiefly on the size of the products to be eliminated. The consequence thereof is that the quantity of washing water in circulation is considerably reduced.

Moreover, when the separators comprise multiple compartments, the arrangement in the latter of adjustable partitions provides the possibility of regulating the orifice constituting the communication between each of the said compartments and the discharge chamber.

In order that the invention may be readily understood, selected embodiments of the same are, by way of example, illustrated by the accompanying drawings, wherein:

Figs. 1 and 2 are sections taken respectively in the transverse plane and the middle longitudinal plane of the launder, showing the application to a multiple compartment separator of the improvement according to the invention in one of its forms;

Figs. 3 and 4 are similar views showing a modification which allows the adjustment of the communication between the compartments of the separator and the discharge chamber of the latter, on each side of the partition provided according to the invention; and

Figs. 5 and 6 are also similar views illustrating a second modification offering the same possibilities of adjustment of the communication between the compartments and the discharge chamber of the separator as the modification illustrated by Figs. 3 and 4.

Referring firstly to Figs. 1 and 2, the washing launder *a* has its width divided by a vertical partition *b* situated in the middle longitudinal plane of the said launder. In accordance with invention, this partition *b* is extended downwardly as shown at *c* so as to divide also the compartments *d* of a separator *e* depending from the bottom *f* of the launder *a*. The discharge of the products of high specific gravity at the base of the apparatus *a* is controlled by means of a slide-valve *g*.

Referring now to Figs. 3 and 4, the launder *a* is also divided by a partition *b* extending downwardly as shown at *c* so as to divide also the compartments *d* of the separator *e*, but at its lower edge this extension *c* of the vertical partition *b* is forked to form two sloping partitions *h*. Moreover a portion of the two sloping lateral walls of the apparatus *e* is formed with a thickening *i* increasing in a downward direction, and possesses elongated

holes *k* which make it possible to adjust the position of the said portion in relation to its fixing bolts *m*, and consequently to adjust the size of the space between the lower edge *h* of the inclined partitions *h* and the said thickenings *i*, i. e. the size of the passage for the products of high specific gravity passing from the compartments *d* towards the base of the apparatus *e* where their discharge is controlled by means of a slide-valve *g*.

Figs. 5 and 6 illustrate an arrangement similar to that illustrated by Figs. 3 and 4, but in which the thickenings *i* according to the last-named figures are replaced by two inclined baffles *n* adjusted through the medium of arms *p* to which they are pivotally connected at *v* and which are rigidly mounted on a shaft rotatably supported in bearings *s* provided in the transverse walls of the separator *e*, so that the baffles *n* may be caused to slide in order to adjust the size of the passage for the products of high specific gravity subsisting between the inclined lateral walls of the apparatus *e* and the lower or outer edge of the said baffles *n*.

I claim:

1. In plants for washing coal and other minerals comprising in combination a transversely extended inclined launder for classifying the materials according to specific gravity by means of a liquid conveying stream and having bottom slots extending the width thereof, and a separator located under a slot, a discharge control partition subdividing the separator below the slot, extending longitudinally in the direction of the launder incline and leaving a free passage between its edges and the side walls of the separator.

2. In plants for washing coal and other minerals comprising in combination a transversely extended inclined launder for classifying the materials according to specific gravity by means of a liquid conveying

stream and having bottom slots extending the width thereof, and a separator located under a slot, a discharge control partition subdividing the separator below the slot and extending longitudinally in the direction of the launder incline, and means for adjusting the distance between the edges of said partition and the side walls of the separator.

3. In plants for washing coal and other minerals comprising in combination a transversely extended inclined launder for classifying the materials according to specific gravity by means of a liquid conveying stream and having bottom slots extending the width thereof, and a separator located under a slot, a discharge control partition subdividing the separator below the slot and composed of a number of planes extending longitudinally in the direction of the launder incline, and means for adjusting the distance between the edge of some of the said planes and the side walls of the separator.

4. In plants for washing coal and other minerals comprising in combination a transversely extended inclined launder for classifying the materials according to specific gravity by means of a liquid conveying stream and having bottom slots extending the width thereof, and a separator located under a slot, a discharge control partition subdividing the separator below the slot and composed of a number of planes extending longitudinally in the direction of the launder incline and leaving a free passage between the edges of said planes and the side walls of the separator, a baffle varying in thickness throughout arranged along a side wall of the separator and one of the faces of which forms the wall of the delivery device, and means for adjusting the position of said baffle.

In testimony whereof I signed hereunto my name.

ANTOINE FRANCE.
